BRAKE VALVE DEVICE

Filed Jan. 21, 1928

INVENTOR
JOSEPH C. McCUNE
BY *Wm. M. Bady*
ATTORNEY

UNITED STATES PATENT OFFICE.

JOSEPH C. McCUNE, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

BRAKE-VALVE DEVICE.

Application filed January 21, 1928. Serial No. 248,334.

This invention relates to an electro-pneumatic brake switch device for controlling the brakes electrically and pneumatically and functioning more particularly in a manner similar to the brake switch device disclosed in my prior pending application, Serial No. 235,450, filed November 25, 1927.

The principal object of my invention is to provide an improved electro-pneumatic brake switch device of the above type.

In the accompanying drawing; Fig. 1 is a side view, partly in section, of the brake control device embodying my invention; Fig. 2 is a plan view, partly in section, taken on the line 2—2 of Fig. 1; Fig. 3 is a sectional view taken on the line 3—3 of Fig. 1; Fig. 4 is a sectional view taken on the line 4—4 of Fig. 1; Fig. 5 is a sectional view taken on the line 5—5 of Fig. 1; Fig. 6 is a fragmentary view showing the means for locking the spindle sleeve to the operating cam; and Fig. 7 is a sectional view taken on the line 7—7 of Fig. 4.

As shown in the drawing the brake switch device comprises a casing 1, having a chamber 2 containing a vertically disposed, rotatable shaft 3, which is adapted to be operated by a lever handle 4. The upper end of the shaft 3 extends through a bearing opening 30 formed in the top wall of the casing, while the lower end of said shaft extends through an opening formed in the lower wall, the shaft having a bearing in the bushing 5, secured in the lower wall of the casing. Within the chamber 2 and adjacent the bushing 5, a cam 6 is secured to the shaft 3 by means of a pin 7.

Mounted on the shaft 3 is a sleeve 9 of insulating material, having notches at the lower end, located non-radially and adapted to receive lugs 10 on the cam 6. Interposed between the upper end of the sleeve 9 and a shoulder 11 of the casing wall is a thrust washer 12, having two radially disposed lugs 13 adapted to engage corresponding notches in the sleeve.

For electrically controlling the sanding of the rails, a switch device is provided, comprising a push rod 14, which slidably extends through a central bore in the shaft 3 and into a chamber 15 formed in a downwardly extending portion of the casing 1 and said push rod has a head or enlarged portion 16 formed

at the lower end and contained in chamber 15. Loosely mounted on the rod 14 and supported by the head 16 are discs 17 of insulating material, having an interposed contact disc 18. The lower end of the shaft 3 is chambered to receive a coil spring 19 which acts to press the discs against the head 16.

The contact disc 18 is adapted upon downward movement to bridge two fixed contacts 20, said contacts being connected to a circuit (not shown), which controls means for effecting the sanding of the rail. The contacts 20 are mounted in a member 21 of insulating material, said member being secured to lugs 22 extending outwardly from the enclosing wall of chamber 15. Downward movement of push rod 14 is opposed by a spring 23 mounted between a cover plate 24, adapted to close chamber 15, and a thrust member 25, having a conical projection 26 adapted to centrally engage the rod head 16. In order to insulate the terminals 27 of the contact 20 from the spring 23, a sleeve 28 of insulating material is mounted on the cover plate 24 in such a manner as to extend upwardly between said terminals and spring.

For rotating the shaft 3 and for operating the push rod 14, a removable handle device is provided comprising a sleeve 30 adapted to be applied to the upper end of the shaft 3 and having a handle carrier portion 29 to which the lever handle 4 is pivotally connected by a pin 39.

The upper end portion of the shaft 3 is encased in a bonnet 31 and the upper end wall of the bonnet is provided with an opening to permit the application and removal of the sleeve 30 of the handle device. When in position, the lower end of the sleeve 30 engages a shoulder 34 formed on the shaft 3.

In order to cause rotation of the shaft 3 upon rotational movement of the lever 4, the sleeve 30 is provided with a square or key sectioned socket adapted to receive a corresponding squared end portion of the shaft 3.

To prevent removal of the handle device except in a predetermined operating position of the shaft 3, I provide a lug 35 on the sleeve portion 30 of the lever carrier 29, which lug is adapted to pass through a notch 37 cut in the upper end wall of the bonnet 31. After the lever is applied in position, rotational movement thereof is limited by two stop lugs 38

formed interiorly on the side wall of the bonnet 31 and adapted to be engaged by the lug 35 upon a predetermined movement of the handle 4 in either direction. Upward vertical movement of the handle lever 4 is limited by a stop pin 40.

Slidably mounted in the sleeve 30 is a plunger 42, and secured to the handle lever 4 is a screw having a hardened button shaped head 41 adapted to engage the upper end of the plunger 42. The plunger 42 is adapted to engage the upper end of the push rod 14, when the handle device is applied to the shaft 3. A member 44, also mounted in the interior of the sleeve portion 30 of the lever, has a central opening, which forms a guide for the lower end of the plunger 42, and has a flange 45 adapted to engage a shoulder formed on the interior wall of the sleeve portion. Interposed between the flange 45 of the member 44 and the lower face of the plunger 42 is a spring 46, which resists downward movement of said plunger and the handle lever 4.

For the purpose of locking the lever 4 in its operative position, a radially disposed plunger pin 47 is provided, which is adapted to engage in a groove 49 formed in the sleeve portion 30. A spring 48 is interposed between a washer 50, secured to the plunger pin, and the interior surface of a member 51, having screw-threaded engagement in the casing, and urges the plunger pin 47 into engagement with the groove 49. The plunger pin extends through the outer wall of the member 51 and is provided with a pull button 52, by means of which the plunger pin 47 may be pulled out of engagement with the groove 49 in the lever sleeve 30.

Contained in a chamber 53, formed in the casing 1, is a double beat valve 54, having at one side a fluted stem 55 extending through a bore in the bushing 56 and into a chamber 57, the bushing 56 being secured in the casing wall by screw-threaded engagement, and having at the opposite side a solid stem 58 extending into the chamber 2 through the bore in a bushing 59. The chamber 57 is closed by a cap nut 60 having screw-threaded engagement in the casing, said cap nut having a chamber in which is slidably mounted a plunger 61 adapted to engage the valve stem 55. Interposed between the cap nut 60 and plunger 61 is a spring 62 tending to hold the double beat valve 54 seated, in the position shown in the drawing.

Pivotedly mounted on a bolt 64 screwed into the lower wall of the casing 1 is an arm 63 and slidably mounted in the outer end portion of the arm is a plunger member 65, which is in engagement with the valve stem 58. The member 65 is acted upon by a spring 66, one end of which is secured to the arm 63 by means of a screw 67. A roller 68 is mounted on the arms 63, preferably intermediate the ends of said arm, and is adapted to be engaged

by a shoulder 69 of the cam 6, upon counter-clockwise rotation of the switch shaft 3.

Mounted in a chamber 75, formed in the casing 1, is a poppet valve 74, having a fluted stem 73 adapted to engage the end of an arm 71, which is pivotally mounted on a bolt 72 secured into the lower end wall of the casing 1. The arm 71 is provided with a roller 70, adapted to be engaged by the cam face 69, when the cam 6 is rotated in a counter-clockwise direction to a sufficient extent. The valve 74 is adapted to normally seat on an annular seat ring 76 formed adjacent the opening in the casing wall, through which the fluted valve stem 73 extends. The valve chamber 75 is closed by a cap nut 77 having screw-threaded engagement in the casing, and having a central chamber containing a spring 78 urging the poppet valve 74 to its seat against the seat ring 76.

In order to define the various braking positions of the lever 4, the cam 6 is provided with a plurality of notches 79 adapted to be engaged by a plunger-like member 80, which is slidably mounted in a bushing 81 secured in the wall of the casing. Interposed between a cap nut 82, having screw-threaded engagement in the casing, and the bottom of a recess 83 formed in the member 80, is a spring 43 urging the member 80 toward the notches 89. The guide portion of the member 80 is provided with a longitudinal slot 84 into which a stop pin 85 projects. Said pin is secured in the wall of the casing and bushing 81 and prevents the plunger member from falling out of place, prior to assembling the cam 6 in position.

A spider-like member 86 is secured to the insulating sleeve 9 by a clamp 87, through the ends of which, cap screws 88 are adapted to pass and engage the spider member by screw-threaded engagement. In order to locate the spider in a predetermined position relative to the insulating sleeve 9, a dowel pin 89 is mounted in the spider and is adapted to enter a corresponding opening in the insulating sleeve.

The spider 86 is provided with a plurality of radiating contact members 90, located in different planes relative to each other, and adapted to engage different flexible contact fingers 91 in different positions of the spider, as the spider is rotated by the handle lever 4. The contact fingers 91 are secured to an insulating member 92, fixed on the side wall of the casing, and are connected with circuit wires 93, which wires are brought together at the bottom of the chamber 2 and from thence are adapted to pass through an opening 94 in the bottom wall of the casing and connect with various brake control devices (not shown) on the car.

Carried by the casing 1 is a bracket or support 95 having an opening 96 through each end, through which bolts, screws or other

securing means may be passed for mounting the brake switch device in a car.

Preferably associated with the brake switch device is a door selector switch mechanism comprising a casing 97 secured to the casing of the brake switch device by bolts 102, and having a chamber 98 containing a vertically disposed shaft 99, rotatably extending through the upper and lower walls 10 of the casing and adapted to be operated by a removable lever handle 100 mounted on the upper enclosed end 111 of said shaft. A sleeve 101, of insulating material, is contained in chamber 98 and is secured on the shaft 99 by means of a pin or rivet 103. A spider 104 is secured to the sleeve 101 in the same manner as the spider 86 is secured to the sleeve 9 in the brake switch device, said spider having a plurality of radiating contact members 105 located in different planes relative to each other and adapted to engage a plurality of flexible contact fingers 106 in different positions of the handle lever 100. The contact fingers 106 are secured to an insulating member 107 mounted on the side wall of the casing 97, said fingers being connected with electric circuit wires 108, which are adapted to pass through the opening 94 in the lower wall of the casing 1 of the brake switch device and from thence to door control magnets (not shown) for controlling the operation of the car doors.

The lever handle 100 is provided with an enlarged end 109 having a recess containing two pins 110, which, when the lever handle is applied, are adapted to project into two corresponding holes in the enlarged upper end 111 of the switch shaft 99. The enlarged end 109 of the lever handle is provided with a groove or slot 112, into which a plunger-like member 113 is adapted to be projected by the pressure of a spring 114. The member 113 is contained in a chamber 115 of a bracket 116 mounted on the casing 97, and has a stem 117 projecting through the end wall of chamber 115 and secured to the outer end of said stem is a button 118 for manually pulling the plunger 113 outwardly, in order to permit removal or application of the lever handle 100. The bottom of the slot 112 is provided with recesses 119, which the plunger 113 is adapted to engage, in order to define the various positions of the lever handle.

The chambers 2 and 98 are adapted to be closed by cover plates 119 and 120 respectively, as partly shown in the drawing, the cover plate 119 being secured to the casing by two thumb screws 121 and the cover plate 120 being held in position by two dowel pins 122, which are secured in the casing and are adapted to enter corresponding holes in the cover plate, in addition to a thumb screw 123.

In operation, the brake switch device is manipulated in substantially the same manner as the brake switch device disclosed in my

previously mentioned, prior pending application, Serial No. 235,450, filed November 25, 1927.

After the lever handle 4 is applied to the shaft 3 by inserting the sleeve portion 30 through the opening in the upper end wall of the bonnet 31, in such a manner that the lug 35 in the sleeve passes through the notch 37 in the bonnet, then the brakes on the car (not shown) may be controlled by rotating the handle 4, such rotation being limited by engagement of the lug 35 on the sleeve with the stop lugs 38 in the bonnet, and causing engagement of the radiating contact members 90 on the spider with the contact fingers 91, in various positions, in accordance with the brake operation desired.

In one position of the lever handle 4, such as service position, the shoulder 69 on the cam 6 engages the roller 68 on the arm 63 and operates said arm in such a manner as to shift and seat the double beat valve 54 in the position opposite to that shown in the drawing, in order to cut off communication from the emergency pipe to the pilot valve so as to prevent an emergency application of the brakes from occurring. In the emergency position of the lever handle 4, the cam shoulder 69 engages the roller 70 and operates the arm 71 in such a manner as to unseat the poppet valve 74, in order to permit fluid under pressure to be vented from the valve chamber 75 and the emergency valve piston chamber, so as to cause an emergency application of the brakes.

The sanding mechanism (not shown) may be operated at any time to sand the rails of the track, since in all positions of the lever handle 4, said handle may be depressed and cause the contact disc 18 to bridge the contacts 21 and thus close the circuit to the sanding mechanism.

The selector door switch device is adapted, in its different positions, to close electric circuits through the control fingers 106 and the contact members 105, so that any desired door or doors of the vehicle will be opened or closed, when the brake switch device is turned to the required position.

It will be noted that the pressure of spring 23 acts through the discs 17 and 18, and the shaft 3, and maintains the shaft 3 and thrust washer 12 in engagement with the shoulder 11 of the casing, so that wear is permitted to occur only between the engaging surfaces of said thrust washer and shoulder.

Since the switch member 18 is pressed into engagement with the contacts 21 by the pressure of spring 19, rupture or distortion of said switch member is prevented by any excess, downward movement of the push rod 14.

It will be noted that relative movement is provided between the arm 63 and the valve operating spring 66, so as to prevent variations in dimensions of the cooperating, oper-

ating parts for affecting improper operation of the double beat valve 54.

While one illustrative embodiment of the invention has been described in detail, it is not my intention to limit its scope to that embodiment or otherwise than by the terms of the appended claims.

Having now described my invention, what I claim as new and desire to secure by Letters Patent, is:—

1. In a brake controlling device, the combination with an operating shaft, of a removable handle device comprising a socket member adapted to be applied to said shaft and a handle pivotally connected to said member.

2. In a brake controlling device, the combination with an operating shaft, of a removable handle device comprising a socket member adapted to be applied to said shaft and a handle pivotally connected to said member for rotating said member and thereby said shaft.

3. In a brake controlling device, the combination with an operating shaft, of a removable handle device comprising a socket member adapted to be applied to said shaft, a handle pivotally connected to said member, and a latch for locking said member against removal.

30 4. In a brake controlling device, the combination with an operating shaft, of a removable handle device comprising a socket member adapted to be applied to said shaft, a handle pivotally connected to said member, and an axially movable rod disposed in said shaft and adapted to be actuated by pivotal movement of said handle.

5. In a brake controlling device, the combination with an operating shaft, of a removable handle device comprising a socket member adapted to be applied to said shaft, a handle pivotally connected to said member, a plunger disposed in the socket of said member and operably by pivotal movement of said handle, and an axially movable rod disposed in a bore of said shaft and operable by the movement of said plunger.

40 6. In a brake controlling device, the combination with an operating shaft, of a removable handle device comprising a socket member mounted on said shaft, a handle pivotally connected to said member, a rod axially mounted in a bore of said shaft and operable upon pivotal movement of said handle, and

an electric switch device operated upon movement of said rod. 55

7. In a brake controlling device, the combination with a rotatable shaft, of a handle device for rotating said shaft, a rod mounted in an axial bore of said shaft and operable by said handle, and an electric switch contact member yieldably mounted on said rod. 60

8. In a brake switch device, the combination with a casing and a rotatable shaft mounted in said casing, of a handle device for rotating said shaft, a thrust washer movable with said shaft and engaging a bearing face on said casing, and a spring acting on said shaft and urging said washer into engagement with said bearing face. 65

9. In a brake controlling device, the combination with a rotatable shaft and a handle device for rotating said shaft, of a cam member carried by said shaft, a pivoted arm operable by said cam upon rotation of said shaft, a valve, a member for operating said valve, and a spring carried by said arm for operating said member and thereby said valve. 70 75

10. In a brake controlling device, the combination with a rotatable shaft and a handle device for rotating said shaft, of a cam member carried by said shaft, a pivoted arm operable by said cam upon rotation of said shaft, a valve operated by said arm upon a predetermined rotative movement of said cam, an additional pivoted arm, and an additional valve operated by said arm, said additional arm being operated upon a further predetermined rotative movement of said cam. 80 85

11. In a brake controlling device, the combination with a rotatable shaft, of a handle device for rotating said shaft, an axially movable rod mounted in said shaft and operable by said handle, an electric contact member carried by said rod, and a spring for yieldingly maintaining said member in position on said rod. 90 95

12. In a brake controlling device, the combination with an operating handle, of a rod operable by said handle, fixed contacts, a movable contact member mounted on said rod for engaging said fixed contacts, and a spring for maintaining said contact member in engagement with the fixed contacts, upon movement of said rod relative to said member. 100 105

In testimony whereof I have hereunto set my hand.

JOSEPH C. McCUNE.
